CLAIM

The ornamental design for a waste basket, as shown and described.

DESCRIPTION

FIG. 1 is a front elevational view of a waste basket showing my new design;

FIG. 2 is a rear elevational view of the waste basket;

FIG. 3 is a left side elevational view of the waste basket, the right side elevational view being symmetrical therewith;

FIG. 4 is a top plan view of the waste basket;

FIG. 5 is a bottom plan view of the waste basket;

FIG. 6 is a perspective view of the waste basket; and,

FIG. 7 is a perspective view of the waste basket shown in a stacked position.

The broken line showing of additional waste baskets in FIG. 7 is for illustrative purposes only and forms no part of the claimed design.
